DISHWASHER

Harrison K. Linger, Wheaton, Ill., assignor to General
Electric Company, a corporation of New York

Filed Sept. 25, 1961, Ser. No. 66,845

Term of patent 14 years

(Cl. D49—1)

FIG. 1

FIG. 2

FIG. 3

FIG. 1 is a front perspective view of a dishwasher, showing my new design;

FIG. 2 is a rear elevational view thereof; and

FIG. 3 is an elevational view thereof taken from the left side of FIG. 1.

The dominant features of my design reside in the portions shown in full lines.

The right side, not shown, is essentially plain.

I claim:

The ornamental design for a dishwasher, substantially as shown and described.
